(57) **CLAIM**

The ornamental design for a medication flavoring container bottle cap, as shown and described.

DESCRIPTION

FIG. 1 is a top and front isometric view of a medication flavoring container bottle cap showing our new design;

FIG. 2 is a bottom and front isometric view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

The broken lines and the unshaded area in between the broken lines depict portions of the medication flavoring container bottle cap that form no part of the claimed design. In FIGS. 2 and 8 the innermost solid line of the bottom of the cap forms the boundary of the claim.
